AMPLIFYING ARRANGEMENT FOR VOLTAGES, PARTICULARLY FOR AUTOMATIC VOLUME CONTROL

Charles Thomas Scully, London W. C. 2, England, assignor, by mesne assignments, to International Standard Electric Corporation, New York, N. Y., a corporation of Delaware

Application February 16, 1943, Serial No. 476,112
In Great Britain February 20, 1942

4 Claims. (Cl. 179—171)

The present invention relates to electrical voltage amplifying arrangements, and more particularly applies to automatic volume control systems.

It is well known that in electrical communication systems, it is very often necessary to provide means for dealing with variations in the signal amplitude, caused for example, by variations in the transmission characteristics of the communication medium due to weather changes and the like. Such means frequently comprise automatic arrangements for adjusting the gain of one or more amplifiers in the system in accordance with the changes in the signal level, so that the level at the output terminals of the amplifier remains substantially constant. These automatic volume control arrangements may be operated by the signals themselves, or by a separate pilot signal provided for the purpose, and subjected to the same changes in the communication medium.

Automatic volume control arrangements are frequently used in radio receivers to counteract fading, and the present invention is of particular (though not exclusive) application to such apparatus.

It is generally the practice to obtain from the incoming signal (or pilot signal) a rectified voltage proportional to the signal amplitude, and to apply this rectified voltage to control the amplification of some convenient valve in one of the amplifiers of the system, for example by means of a control grid. The control voltage is obtained by tapping off the signals, possibly at an intermediate frequency stage, then amplifying, and then rectifying the amplified signals. It is usually necessary also to amplify the rectified signals, and for this purpose a valve is required whose high tension supply must be derived from a separate direct current source.

The present invention provides a simpler means for obtaining a large controlling voltage or power by avoiding the necessity for any large amount of high frequency amplification or for a separate direct current source.

The invention accordingly comprises an arrangement for obtaining a continuous volume control voltage for signals transmitted over a communication medium of variable transmission characteristics, in which a rectifier is provided for obtaining a continuous voltage from an alternating current supply source to serve as the said control voltage, the output of the said rectifier being controlled by a rectified voltage obtained

from the said signals, or from a separate pilot signal transmitted over the same medium.

The invention will be more clearly understood from the following detailed description which refers to the accompanying drawing Figs. 1 and 2 of which show schematic circuit diagrams of two embodiments.

Referring to Fig. 1, the signals for operating the automatic volume control are tapped off the channel through the transformer 2 connected to the anode and cathode of a diode 1 through a resistance 3 shunted by a condenser 4. A rectified voltage proportional to the amplitude of the signals will be developed across resistance 3 the alternating currents being by-passed by the condenser 4; and the cathode end of the resistance will be positive to the other end. The resistance 3 is connected between the cathode and control grid of a valve 5, a grid biasing battery 12 being included as shown, having suitable polarity and voltage to adjust the position of the operating point on the valve characteristic. Any other convenient biasing arrangement may be used. The cathode of valve 5 is connected to earth, and the anode is connected through an appropriate load resistance 6 to one terminal of a suitable alternating current supply (such as a transformer connected to the commercial supply) the other terminal of which is earthed. The anode is also connected to an output terminal 10 through a smoothing network comprising the series resistance 7, and the shunt condensers 8 and 9. The second output terminal 11 is connected to earth, and the voltage difference between 10 and 11 is applied in any convenient known way to control the amplifier gain.

It will be seen that the valve 5 acts a rectifier to produce a continuous voltage from the alternating current supply, the magnitude of which is controlled by voltage developed by the incoming signal across resistance 3. Owing to the load resistance 6, and on account of the fact that there will be substantially no anode current in the valve 5 for the negative half-waves, the anode voltage will be practically the same as the applied voltage for the negative half-waves. Owing, however, to the current which flows during the positive half-waves, the anode voltage will be lower than the applied voltage. Thus in the rectified output, terminal 10, which is connected to the anode, will be negative to terminal 11.

When the signal amplitude increases, the voltage across the resistance 3 increases, making the control grid of valve 5 more positive. This will reduce the anode voltage for the positive half-

waves, and the negative voltage of terminal 10 will be accordingly increased, and the change will be amplified by the valve 5. On the basis that an increase in the negative voltage is a negative change, the arrangement may be considered to produce a change of the controlling voltage in the opposite sense to the change in the signal level, or alternatively it may be considered that a phase change of 180 degrees is produced. If this phase change is inconvenient, the diode 1 may be 10 reversed so that the anode instead of the cathode is connected to the control grid of the valve 5. An increase in the signal amplitude will then cause a reduction in the negative control voltage.

Fig. 2 shows a modification of Fig. 1 in which the valve 5 has been inverted in order to produce a positive instead of a negative control voltage on terminal 10. The anode is connected to earth and the cathode to the load resistance 6, the resistance 3 being connected between the cathode and the control grid. The rectified voltage of the cathode will now be positive to the anode, and terminal 10 will now be positive to terminal 11.

When the diode is connected as shown in Fig. 2, an increase in the signal level makes the control grid more negative. This reduces the negative rectified voltage so that the positive voltage of terminal 10 with respect to terminal 11 is also reduced, and a phase change of 180 degrees (that is, a change in the opposite sense) will be produced as in the case of Fig. 1. By reversing the diode an increase of the signal level will be made to increase the positive voltage of terminal 10, and the change will be in the same sense.

It will thus be seen that the connection of the valve 5 decides the polarity of the control voltage, and the connection of the diode 1 denotes whether or not a phase change will be introduced, so that an arrangement suitable for any particular case can be produced.

Various minor modifications of the arrangement shown in the accompanying figures are possible to suit practical cases. For example, the diode 1 could be replaced by a triode or pentode suitably biased for rectification, or a metal rectifier could be used. The smoothing network 7, 8,

9, could be replaced by a low pass filter having the cut-off frequency a little below the frequency of the supply. It might also be necessary to connect a low pass filter between the resistance 3 and the control grid of the valve 5 for excluding the signal or pilot frequency. Further, the grid biasing arrangement, shown as a battery 12 in the figure, could be one of any of the well known means for this purpose. It is not intended that the invention should be limited to the embodiments shown and described.

What is claimed is:

1. System for obtaining a continuous volume control voltage for signals transmitted over a communication medium of variable transmission characteristics, including a rectifier fed by said signals, a thermionic valve, means connecting the output of said rectifier to the input electrodes of said valve, a source of alternating current supply, one terminal of said alternating current supply being connected to the cathode of said valve, and the other terminal to the anode thereof, a load resistor in series with said supply, and an output circuit connected directly between said cathode and said anode so as to shunt said electrodes.

2. System according to claim 1, including a resistance in the output circuit of said rectifier, said thermionic valve having its control grid and cathode connected respectively to the terminals of said resistance.

3. System according to claim 1, including a resistance in the output circuit of said rectifier, in which the control grid of said thermionic valve is connected to the junction point of said resistance and said rectifier, whereby the rectifier connections are so poled that the changes in the signal amplitude cause the control voltage to change in the opposite sense.

4. System according to claim 1, including a resistance in the output circuit of said rectifier, in which the cathode of said thermionic valve is connected to the junction point of said resistance and said rectifier, whereby the rectifier connections are so poled that the changes in the signal amplitude cause the control voltage to change in the same sense.

CHARLES THOMAS SCULLY.
